DISPENSER FOR COILED SHEET MATERIAL OR THE LIKE

James F. Fulton, Mamaroneck, N.Y., assignor to Reynolds
Metals Company, Richmond, Va., a corporation of Virginia

Filed Apr. 8, 1963, Ser. No. 74,342

Term of patent 14 years

(Cl. D52—2)

FIG. 1 is a front perspective view of a dispenser for coiled sheet material or the like embodying my new design;

FIG. 2 is a rear perspective view thereof;

FIG. 3 is a side elevational view thereof;

FIG. 4 is a cross sectional view taken on line 4—4 of FIG. 1; and

FIG. 5 is an enlarged fragmentary perspective view of the cutter portion thereof.

I claim:
The ornamental design of a dispenser for coiled sheet material or the like, as shown.
